UNITED STATES PATENT OFFICE.

PHILO SYLLA, OF ELGIN, AND AUGUSTUS ADAMS, OF SANDWICH, ILLINOIS, ASSIGNORS TO C. AULTMAN & CO., OF CANTON, OHIO.

IMPROVEMENT IN GRAIN AND GRASS HARVESTERS.

Specification forming part of Letters Patent No. 10,038, dated September 29, 1853; Reissue No. 723, dated May 17, 1859.

DIVISION C.

To all whom it may concern:

Be it known that PHILO SYLLA, of Elgin, in the county of Kane and State of Illinois, and AUGUSTUS ADAMS, formerly of the same place, but now residing at Sandwich, in the county of De Kalb, in said State, invented certain new and useful Improvements in Machines for Harvesting Grain, Mowing Grass, &c., of which the following is a full, clear, and exact description, reference being had to the annexed drawings, which make part of this specification, and in which—

Figure 1 is a view in perspective of a machine, showing one mode of applying said improvements, the finger-beam being raised from the ground to adapt the machine for reaping. Fig. 2 represents a plan of a portion of the under side of the machine to exhibit more fully the flexible connection of the finger-beam with the main frame. Fig. 3 represents a plan of the machine, the finger-beam resting on the ground to adapt the machine for mowing. Fig. 4 represents a vertical transverse section of the machine at the line 1 1 of Fig. 3. Fig. 5 represents a vertical longitudinal section of the same at the line 2 2 of Fig. 3; and Fig. 6 represents a plan of the cutting apparatus, the finger-beam, and the coupling-arm for connecting the finger-beam to the main frame. Fig. 7 is a vertical section at the line 3 3 of Fig. 6, showing the provision for allowing play in the joint between the finger-beam I² and the yielding bar K.

That side of the machine which runs next the standing grain we call the "left" side, and the other, at which the horses are placed, we call the "right" side.

The accompanying drawings represent a machine having a frame large enough to support, in addition to the cutting apparatus and machinery required for mowing, a removable platform placed behind the cutter, (such as is common in ordinary machines adapted to reaping and mowing,) an elevated table behind the platform to bind the grain upon, stands for a raker and binders, a dumping-tray to carry the sheaves until a sufficient quantity for a shock has accumulated and then to dump them in a heap upon the ground, and a stand or

place for the driver of the team by which the machine is drawn.

Whenever it may be expedient to use one or more of the several parts or branches of said improvements separate from the rest, such part or parts might be used in connection with frames and gearing more convenient than those herein described, which are proportioned and arranged with reference to the use of the whole of the parts together, and it is obvious that several parts of the said improvements are applicable to various other reaping or mowing machines in use. One mode of applying each of these improvements to practical use is shown in this machine. It is therefore unnecessary to specify the manner of applying the parts, respectively, to other machines, as the ordinary skill of a constructor is sufficient for that purpose.

In machines for mowing it is important for the cutting apparatus to run, as nearly as possible, parallel with the surface of the ground, and as this surface is generally more or less undulating it is necessary that the finger-beam should rise and fall freely, to ascend and descend the sides of the undulations that cross the swath at right angles, and to sway freely up and down at both ends to accommodate itself to the sides of the undulations that cross the swath obliquely, and to the varying transverse inclinations of the surface of the swath. Such swaying and rising and falling of the finger-beam is much more free, and the finger-beam follows the surface of the ground much more readily when its ends are equally free to rise and fall; but such freedom is much interfered with when the finger-beam projects beyond the ends of the cutter farther than is necessary for the purpose of protecting it, first, because the length of the beam is increased by such projection, and the cutter thereby prevented from cutting as near the ground, wherever the latter is a curve of which the finger-beam is the cord, as it would do if the finger-beam were shorter; second, because the projecting end of the finger-beam would often pass along a ridge and hold up one end of the cutter at a distance from the ground beneath it, when the finger-beam, but for such projection, would

have passed along without reaching the ridge, and of course closer to the ground, carrying the cutter and cutting the stubble shorter; and, third, because the shorter a finger-beam is, which is free to rise and fall at both ends, other things being equal, the more closely it will conform and the nearer it will cut to the surface of uneven ground; and the invention which is the subject of this patent consists in the combination of a short finger-beam—*i. e.*, one of only sufficient length to protect the cutting apparatus, and not extending beyond the end of the cutter across the gearing-frame, like the ordinary long finger-beam, which is often made half as long again as the cutter—with a yielding coupling-arm or the equivalent thereof to connect the finger-beam with the main frame in such manner as to allow both ends and either end of the beam to rise and fall to accommodate itself to the surface of the ground.

In the accompanying drawings, the main frame A A' A² A³ A⁴ B B' B² B³ E E' E² is supported upon two wheels, D and D', whose journals rest in bearings in blocks C C', made adjustable to set the frame at a variable distance from the ground. This frame is heavier in front of than behind the axis of the wheels D D' and the preponderating weight is sustained by a truck in front, composed of two wheels, E³ E², and an axle, F, and connected with the main frame by a draft-bar, F², hinged at its rear end on a pivot, F⁴, to the beam A' of the frame. For the purpose of allowing the front of the main frame to be raised, lowered, and held at different heights the draft-bar passes through a strap, F³, attached to the beams E and A', and a wedge placed between the top of the strap and the draft-bar holds the front of the frame at any required height within the range of adjustment allowed by the strap, and it may be lowered by withdrawing the wedge, and may be held down by placing the wedge between the under side of the draft-bar and the bottom of the strap. A like effect may be produced by passing a pin through the strap above or below the draft-bar in the holes made for the pin in the sides of the strap. By these means the connection of the draft-bar with the frame may by turns be limber or rigid, and the front of the frame set at various heights from the ground. When the wedge and pin are withdrawn the front of the main frame and the front end of the tongue respectively are free to play up and down within the limits of the strap independently of each other. The ends attained by the adjustment already described may likewise be attained, to a certain extent, by adjusting the pivot F⁴, on which the rear end of the draft-bar F² hinges, from one hole to another in a series formed for its reception in the side of the beam A'.

The tongue F', by which the horses draw the machine, is attached to and extends forward from the axle of the truck.

The motion of the cutter in this machine is derived from one of the wheels which carry the

main frame. On the side of the right wheel, D, a bevel-wheel, G, is secured, which takes into and drives a pinion, G', on a counter-shaft, G², which also carries a spur-wheel, G³, that takes into and drives a pinion, G⁴, on the end of a shaft, whose opposite end carries a crank, H, which, through a connecting-rod, H', jointed to the cutter-bar H², communicates a vibratory motion to a cutter arranged to play through a series of guard-fingers, J², projecting from the front side of the finger-beam I². The bearing of that end of the shaft G² which carries a pinion, G, is in an upright arm, H³, hinged at its lower end to the frame, so that by turning this arm toward or from the wheel D the pinion may be thrown into or out of gear with the wheel, to put the cutter into or out of motion. The pinion is held in either position at will by means of a notched detent, I, pivoted to the main frame.

The cutter H² and guard-fingers J² are of the usual construction and supported by the finger-beam in the usual manner.

The right end of the finger-beam I² is connected to the frame by means of a strong link or coupling-arm, J, hinged at its left end to the right end of the finger-beam, and at its right end to a cross-beam, E', of the main frame.

The progressive motion of the frame on its wheels carries forward the coupling-arm, and that in its turn carries forward the finger-beam and cutter, and as the coupling-arm is rigid laterally only and its left end, to which the finger-beam is connected, free to rise and fall, the finger-beam necessarily rests on the surface of the ground. Therefore, in passing over undulating ground the finger-beam will rise or fall at either or both ends and sway up and down within certain limits to conform to the surface of the ground.

The coupling-arm and finger-beam are supported by a yielding bar or brace, K, extending from the junction of the left end of the coupling-arm with the right end of the finger-beam, backward, and connected by a hinge, K², to the cross-bar B³ of the frame. The rear end of the bar K is extended some distance behind its hinge K² and is enlarged to counterbalance the weight of its front end and that of the coupling-arm and of the connecting-rod, which gives motion to the cutters, so that the right end of the finger-beam may bear as lightly on the ground and be as free to rise and fall as the left end. Since, however, this machine is designed for reaping as well as mowing, and must therefore be capable of carrying a platform whenever it is required to be used as a reaper, and when so used must likewise be capable of carrying the finger-beam at a height of several inches above the ground, a second yielding bar, K', is provided to support the left end of the finger-beam, to which it is attached at its forward end and is hinged to the side rail, A², of the frame on a pivot, K⁴. The finger-beam being thus connected with the driving-wheel and with the frame for supporting the gearing, so as to leave it free to rise

and fall at both ends, and at either end, within certain limits, without disturbing the level of the other, these movements are greatly facilitated and the adaptability of the finger-beam to the varying inclinations of the surface of the ground greatly promoted, as the said inventors discovered, by making the finger-beam short, as represented in the drawings—*i.e.*, of only sufficient length to protect the cutting apparatus, and not long enough to extend beyond the cutter-bar across the gearing-frame, as is common when the finger-beam is rigidly connected to the frame.

As the platform upon which the grain collects as it is cut, the table upon which it is bound into sheaves, and the tray for carrying the sheaves until a quantity suitable for a shock has accumulated and then dumping them in a heap, form no part of the subject-matter of the

claim under this patent, a further description of them here is deemed unnecessary.

What is claimed in this patent as the invention of the said SYLLA and ADAMS is—

The short finger-beam, in combination with the yielding connection with the main frame or its equivalent, substantially as herein set forth.

In testimony whereof we have hereunto subscribed our names.
